US00D882761S

(12) **United States Design Patent** (10) Patent No.: **US D882,761 S**
(45) Date of Patent: **** Apr. 28, 2020**

(54) **INJECTOR DEVICE**

- (71) Applicant: **West Pharma. Services IL, Ltd.**, Ra'anana (IL)
- (72) Inventors: **Oz Cabiri**, Hod Hasharon (IL); **Reuven Y. Filman**, Tel Mond (IL); **Boris Degtiar**, Modiin (IL); **Ofer Zick**, Tikva (IL)
- (73) Assignee: **West Pharma. Services IL, Ltd.**, Ra'anana (IL)
- (**) Term: **15 Years**

(21) Appl. No.: **29/697,035**

(22) Filed: **Jul. 3, 2019**

Related U.S. Application Data

- (63) Continuation of application No. 29/628,592, filed on Dec. 6, 2017, now abandoned, which is a continuation of application No. 15/395,166, filed on Dec. 30, 2016, which is a continuation of application No. 13/892,905, filed on May 13, 2013, now Pat. No. 9,572,926, which is a continuation of application No. 13/272,555, filed on Oct. 13, 2011, now Pat. No. 8,465,455, which is a continuation of application No. 12/559,563, filed on Sep. 15, 2009, now Pat. No. 8,157,769.

CLAIM

The ornamental design for an injector device, as shown and described.

DESCRIPTION

FIG. 1 is a front, left side isometric view of an injector device in accordance with our new design;

FIG. 2 is a front, right side isometric view thereof; and,

FIG. 3 is a left side elevational view thereof.

The dash-dot broken lines define a boundary of the injector device that forms no part of the claimed design. The

(Continued)

dash-dash broken lines depict portions of the injector device that form no part of the claimed design.

1 Claim, 3 Drawing Sheets
